(57) **CLAIM**

The ornamental design for a light fixture, as shown and described.

DESCRIPTION

FIG. 1 is a perspective view of a light fixture in accordance with my design;

FIG. 2 is a top plan view of the light fixture in accordance with my design;

FIG. 3 is a bottom plan view of the light fixture in accordance with my design;

FIG. 4 is a front elevation view of the light fixture in accordance with my design, the opposite side being a mirror image of that shown;

FIG. 5 is a side elevation view of the light fixture in accordance with my design, the opposite side being a mirror image of that shown.

The broken lines shown in FIGS. 1, 2, 4 and 5 depict support rods that form no part of the claimed design.
